Patented May 4, 1976

239,749

SOAP REST

Irene Rose, 338 E. 55th St., New York, N.Y. 10022

Filed Apr. 2, 1975, Ser. No. 564,311

Term of patent 14 years

Int. Cl. D23—02

U.S. Cl. D6—89

FIG. 1 is a side elevational view of a soap rest showing my new design;

FIG. 2 is a top plan view;

FIG. 3 is a bottom plan view;

FIG. 4 is a front elevational view;

FIG. 5 is a rear elevational view; and

FIG. 6 is a reduced perspective view.

I claim:

The ornamental design for a soap rest, substantially as shown.
